(57) CLAIM

The ornamental design of a pet chew toy, as shown and described.

DESCRIPTION

FIG. 1 is a perspective view of the pet chew toy of my new design;

FIG. 2 is a side view thereof which, due to the symmetry of the design, is identical to the opposite side view;

FIG. 3 is a top plan view thereof which, due to the symmetry of the design, is identical to the bottom, front and rear views thereof; and,

FIG. 4 is a sectional view thereof taken through line 4—4 in FIG. 3 showing the hollow interior of the toy.
